(57) **CLAIM**

The ornamental design for a model vehicle bed rail as shown and described.

DESCRIPTION

FIG. 1 is a top, left, front perspective view of a model vehicle bed rail showing our new design;

FIG. 2 is a top, right, rear perspective view thereof;

FIG. 3 is a bottom, right, front perspective view thereof;

FIG. 4 is a bottom, left, rear perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a right-side elevation view thereof; and,

FIG. 10 is a left-side elevation view of the model vehicle bed rail.

The broken lines illustrate portions of the model vehicle bed rail that form no part of the claimed design. Only the left-side model vehicle bed rail is shown. The right-side model vehicle bed rail is a mirror image of the claimed model vehicle bed rail and is intended to represent a claimed second embodiment.
